UNITED STATES PATENT OFFICE

124,881

DESIGN FOR A COVERED BOWL OR THE LIKE

Joseph R. Thompson, East Liverpool, Ohio, assignor to The Hall China Company, East Liverpool, Ohio

Application September 23, 1940, Serial No. 95,310

Term of patent 7 years

To all whom it may concern:

Be it known that I, Joseph R. Thompson, a citizen of the United States, residing at East Liverpool, in the county of Columbiana and State of Ohio, have invented a new, original, and ornamental Design for a Covered Bowl or the like, of which the following is a specification, reference being had to the accompanying drawing, forming a part thereof.

I claim:

The ornamental design for a covered bowl or the like, as shown.

JOSEPH R. THOMPSON.
